DESIGN FOR A LIGHT FIXTURE

Charles A. Trowbridge, Roxborough, Pa., assignor
to Taber Associates, Philadelphia, Pa., a firm
composed of Philip Taber and Richard C. Paige

Application February 6, 1947, Serial No. 136,721

Term of patent 3½ years

(Cl. D72—1)

To all whom it may concern:

Be it known that I, Charles A. Trowbridge, a citizen of the United States, residing in Roxborough, Philadelphia County, Pennsylvania, have invented a new, original, and ornamental Design for a Light Fixture, of which the following is a specification, reference being made to the accompanying drawing, forming part thereof, in which:

Fig. 1 is an end elevational view of a light fixture showing my new design.

Fig. 2 is a front elevational view thereof.

Fig. 3 is a rear elevational view thereof; and
Fig. 4 is a top plan view thereof.

I claim:

The ornamental design for a light fixture, substantially as shown.

CHARLES A. TROWBRIDGE.
